UNITED STATES PATENT OFFICE.

RUDOLPH W. MENK, OF JOLIET, ILLINOIS, ASSIGNOR TO THE EXCELSIOR STEEL FURNACE COMPANY, OF CHICAGO, ILLINOIS, A CORPORATION OF ILLINOIS.

KILN-FURNACE.

1,309,213.

Specification of Letters Patent.

Patented July 8, 1919.

Application filed August 28, 1918. Serial No. 251,751.

To all whom it may concern:

Be it known that I, RUDOLPH W. MENK, a citizen of the United States, and a resident of the city of Joliet, in the county of 5 Will and State of Illinois, have invented certain new and useful Improvements in Kiln-Furnaces, of which the following is a specification.

My invention relates to brick kilns and 10 more particularly to the construction of the furnace or burner employed in connection therewith.

In structures of this type, it is usually the practice to produce and maintain in the 15 kiln a sufficient temperature in order to thoroughly bake the bricks. In the ordinary type of furnace, it has been the practice to provide grate bars onto which fuel is fed which burns in the manner of the 20 ordinary updraft furnace. It will be appreciated that a considerable loss of heat units is occasioned by such a structure as there is a considerable quantity of volatile combustible matter which is liberated upon 25 the heating of the fuel before the volatile matter reaches a temperature at which combustion takes place and which therefore passes away without combustion and without producing any heat. This requires the 30 consumption of considerably more fuel than is necessary in a furnace of the type I have designed. It might be here stated that I employ the principles of a down draft furnace or heater, thereby causing the given 35 off gases to be carried through the burning fuel and consumed therein so that a greater portion, if not all of the heat units are developed. In attempting to operate structures of this kind upon the down draft 40 principle, serious obstacles have been met which have been difficult to overcome, the chief of which is the burning out of the grates and other portions of the structure, owing to the intense heat. It is therefore an 45 object of my invention to provide a brick kiln furnace that is operated upon the down draft principle and which is so constructed that the burning out of the parts is obviated to a more or less extent, and at the 50 same time provide in such a structure an arch or bridge that may be readily replaced in the event such contingency arises. It has also been found in furnaces that, after the 55 temperature of the fuel is raised, there is a material expansion in the body of the fuel

which causes the fuel to become jammed and clogged between the vertical walls of the furnace which interferes with the feeding of the fuel by gravity, the passage of a suitable amount of air therethrough to provide the requisite draft therethrough, and frequently causes the formation of a solid "bridge" or wall above the hot mass of fuel which is difficult to break down and unless it receives attention at the proper time, interferes with the economical functioning of the furnace. In the designing of my present furnace, I have taken care of this contingency by the provision of a removable fire-box or furnace liner the interior surfaces whereof are inclined outwardly and downwardly which affords room for the expansion of the fuel as it becomes heated, so that the jamming thereof and the formation of the fuel "bridge" above referred to are prevented. This liner is also vertically corrugated which materially assists in maintaining a suitable draft. I also provide a structure that is novel in construction, simple in operation and extremely inexpensive and economical to manufacture and operate, and which at the same time is easily repaired or parts replaced, without having to shut down the entire kiln or disturb the other furnaces. 85

I prefer to accomplish the divers objects of my invention by substantially the means and in the manner hereinafter described and as pointed out in the claims, reference being had now to the accompanying drawings that form a part of this specification, in which,— 90

Figure 1 is a longitudinal, vertical section of a furnace for a brick kiln, showing the walls of the kiln in fragmentary section and my improvements installed therein. 95

Fig. 2 is a vertical elevation taken on line 2—2 of Fig. 1.

Fig. 3 is a perspective view of an arch 100 that I prefer to employ.

Referring to the drawings wherein the same reference characters designate like parts throughout the views, it will be observed that A designates the exterior kiln 105 wall that is usually circular in outline and of a height in proportion to the size and shape of the kiln for which it is designed. This kiln wall A, at the place for the location of the furnace, is pierced to provide 110

an opening E of a suitable height for the installation of the grates and arch hereafter to be described.

Back of the opening E in the kiln wall 5 is an interior or baffle wall B that extends to approximately the same height or a little lower than the exterior wall, for the purpose of directing the heat to and adjacent the dome C of the kiln.

10 The furnace comprises horizontal grate bars 5 that are supported at their inner ends on cross bar 6 secured to the vertical inner wall B and said grate bars extend to and slightly in front of the inside surface of the exterior wall A and are supported on a suitable transverse member F mounted in the kiln wall transversely of the opening E. These grates are preferably of the rocker type and are provided with a shaker bar 5^a 15 that extends forwardly from the outer end of one of the grate bars to or through the casting of the furnace, so that these inner grates may be shaken to remove the ashes from the same into the ash-pit. An ash-pit D is provided below the grate bars 5 and extends through the kiln wall A into the lower portion of the furnace and access is had to this ash-pit through the usual ash-pit opening in the front wall 8 of the furnace that is closed 20 by a suitable door 7.

The furnace comprises a vertical wall or shell 8, in which the ash-pit opening and door 7 are provided, and is also provided with a suitable top 9 of a dome-shape or inclined as shown, in which is a fuel or draft door 10. A counter balance chain 11 and weight 11^a are connected with this door 10 so that the latter may be adjusted to divers positions in order to provide suitable draft. 35 40 Inclined grate bars 12 extend upwardly and outwardly from the outer ends of the grate bars 5 to and are secured to the exterior wall 8 of the furnace, as shown, and the top of the opening E, heretofore mentioned, in the kiln wall A, is bridged by an arch of peculiar and special construction.

The sides of the opening E are provided with shelves 13, upon which the arch is mounted and said arch preferably comprises 50 a block of fire brick or the like, 14. Suitable supporting legs 15 are provided at each end of the brick 14, and the space intermediate said legs is arched, as shown in detail in Figs. 2 and 3 of the drawings. The front 55 of the arch brick is provided with an up-standing portion 16, that extends longitudinally thereof in order to protect the outer surface of the kiln wall A, as shown in Fig. 1, and the main body portion 17 affords a 60 platform that extends beneath the wall A of the kiln above the opening E and affords protection thereto. The transverse sectional form of the brick forming the arch is of the particular shape shown in Figs. 1 and 65 3 and is provided with transverse vertical

ribs 18 that afford suitable draft passages when the fuel is banked against them in the usual manner. The front corrugated surface of the arch brick is inclined downwardly and rearwardly as shown.

Similar bricks 14^a and 14^b are positioned within the furnace as shown in Figs. 1 and 2 so as to extend forwardly from the ends of the arch brick 14 to the front wall of the furnace casing and thereby provide above 75 the fuel holding grates a chamber of downwardly increasing capacity whereby the expansion of the fuel is provided for and the formation of fuel "bridges" is prevented.

In Fig. 1 I have shown the manner of firing the kiln above described, wherein it will be observed that after the fire has been started, the burning fuel is pushed back upon the grates 5 and the new fuel is added through the draft door 10 and the fuel door 19 in the 80 front of the furnace, until the fuel has been piled up and covers the arch. The doors 19 and 7 are kept closed and the draft door 10 is opened in order to permit of a down draft through the fuel. As the fuel in the furnace chamber in front of the kiln wall A becomes heated and then ignited, the smoke and volatile gases from the fuel will pass through the burning fuel on the grate bars 5 and be consumed and develop heat units, 95 passing up into the kiln in the usual manner. As fast as the fuel in the outside chamber of the furnace is consumed, the ashes from the burned fuel on grates 5 are shaken down into the ash-pit, the hot coals on the grates 100 12 are pushed back to take their places on the grate 5, and fresh fuel is added, in the manner above described. In the event the arch should burn out from any one of the series of furnaces about a single kiln, the particular furnace thus disabled may be cooled by dropping the coals into the ash-pit and then the arch bar 14 may be removed and a new one replaced and that furnace started again. This will enable the remaining furnaces to be continued in use without materially affecting the operation of the kiln.

I have herein illustrated a specific manner of carrying out my invention, but I desire it understood that the drawings are merely diagrammatic for the purpose of illustrating the principles involved, and it is quite obvious that changes and modifications thereof may be made without materially departing therefrom. For example, the structure herein disclosed in connection with a kiln furnace may be easily applied to furnaces of other types. I therefore desire it understood that I do not limit myself to the precise construction and disposition of the 115 120 125 parts shown and described.

What I claim as new is:

1. A furnace comprising a casing, a wall dividing said casing into opposite compartments and having an aperture therein af- 130

fording communication between said compartments, a burning grate in one of said compartments, a fuel supporting grate in the opposite compartment, the adjacent 5 ends of said grates meeting in and at a point below the top of said aperture, a lintel in the top of said aperture consisting of a fire brick the surface whereof disposed in said fuel compartment is inclined down-
wardly and outwardly toward the fuel sup-
porting grate, similar fire brick extending forwardly of said lintel in the walls of said compartment above said fuel supporting
grate, and means for admitting draft above
said fuel supporting grate.

2. A furnace comprising a casing, a wall dividing said casing into opposite compartments and having an aperture therein afford-
ing communication between said com-
partments, a burning grate in one of said compartments, a fuel supporting grate in the opposite compartment, the adjacent ends 20 of said grates meeting in and at a point below the top of said aperture, a removable
lintel in the top of said aperture consisting
of a fire brick the surface whereof disposed
in said fuel compartment is provided with
vertical corrugations and inclined down-
wardly and outwardly toward the fuel sup-
porting grate, similar fire brick extending
forwardly of said lintel in the walls of said
compartment above said fuel supporting
grate, and means for admitting draft above
said fuel supporting grate.

3. A furnace comprising communicating
compartments, a burning grate located in
one of said compartments adjacent the place
of communication, a fuel supporting grate
located in the other of said compartments in-
clined to the place of communication between
said compartments and to said burning grate,
a removable lintel above the place of com-

munication between said compartments said
lintel having decreasing cross-sectional di-
mensions from the top to the bottom, mem- 45
bers similar in form to said lintel extending
forwardly therefrom in the wall of the com-
partment in which said fuel supporting
grate is installed, and means for admitting a
draft above said fuel supporting grate. 50

4. In firing means for kilns comprising
fuel retaining walls, a wall provided with an
opening through which communication is
had to the interior of the kiln, a lintel for
said opening consisting of a fire brick the 55
surface whereof is inclined downwardly and
outwardly and provided with transverse cor-
rugations.

5. In firing means for kilns comprising
fuel retaining walls, a wall provided with 60
an opening through which communication
is had to the interior of the kiln, a lintel for
said opening consisting of a fire brick hav-
ing decreasing cross-sectional dimensions
from the top to the bottom and provided 65
with vertical corrugations upon its inclined
surface.

6. In firing means for kilns comprising
fuel retaining walls, a wall provided with an
opening through which communication is 70
had to the interior of the kiln, a lintel for
said opening of decreasing cross-sectional
dimensions from the top to the bottom and
having transverse corrugations, and mem-
bers similar in form to said lintel extending 75
forwardly therefrom in said fuel retaining
walls.

Signed at Chicago, county of Cook and
State of Illinois, this 21st day of August,
1918.

RUDOLPH W. MENK.
